UNITED STATES PATENT OFFICE.

DUDLEY M. TODD, OF CHICAGO, ILLINOIS, ASSIGNOR TO DRYDEN RUBBER COMPANY, OF CHICAGO, ILLINOIS, A CORPORATION OF ILLINOIS.

DESIGN FOR A RUBBER SOLE.

Application filed February 13, 1922. Serial No. 685. Term of patent 14 years.

To all whom it may concern:

Be it known that I, DUDLEY M. TODD, a citizen of the United States, residing in Chicago, in the county of Cook and State of Illinois, have invented a new, original, and ornamental Design for Rubber Soles, of which the following is a specification.

In the accompanying drawing, forming part of this specification—

Figure 1 is a bottom view in elevation, and Figure 2 a sectional view on lines 2--2 of Figure 1 of a rubber sole embodying my invention.

I claim:

The ornamental design for a rubber sole as shown.
